A. L. MURRAY

RUBBER SOLE FOR SHOES

Filed Nov. 19. 1924

INVENTOR

Albert L. Murray

UNITED STATES PATENT OFFICE.

ALBERT LINN MURRAY, OF AUBURN, INDIANA, ASSIGNOR TO AUBURN RUBBER CO.,
OF AUBURN, INDIANA.

DESIGN FOR A RUBBER SOLE FOR SHOES.

Application filed November 19, 1924. Serial No. 11,408. Term of patent 3½ years.

To all whom it may concern:

Be it known that I, ALBERT LINN MURRAY, a citizen of the United States, residing at Auburn, in the county of De Kalb and State of Indiana, have invented a new, original, and ornamental Design for a Rubber Sole for Shoes, of which the following is a specification, reference being had to the accompanying drawing, wherein the figure is a bottom plan view of a shoe sole showing my new design.

I claim:

The ornamental design for a rubber sole for shoes, as shown.

October 30, 1924.

ALBERT LINN MURRAY.
